Primary Examiner — John R Yeh*Assistant Examiner* — Dustin Andrew Griffith*(74) Attorney, Agent, or Firm* — Volpe Koenig(57) **CLAIM**

The ornamental design for a protected wearable as shown and described.

DESCRIPTION

FIG. 1 is a front perspective view of the protected wearable showing my new design;

FIG. 2 is a top plan view thereof;

FIG. 3 is a bottom plan view thereof;

FIG. 4 is a left side elevation view thereof;

FIG. 5 is right side elevation view thereof;

FIG. 6 is a front elevation view thereof; and,

FIG. 7 is a rear elevation view thereof.

The broken lines depict portions of the protected wearable that form no part of the claimed design.

1 Claim, 5 Drawing Sheets(56)
